Delos S. Hayes
Attorney.

UNITED STATES PATENT OFFICE

ALBERT W. GODFREY, OF EAST ST. LOUIS, ILLINOIS

HARNESS

Application filed August 5, 1929. Serial No. 383,443.

This invention relates to harnesses, and with regard to certain more specific features to rubber harnesses for horses and other animals.

5 Among the several objects of the invention may be noted the provision of a harness composed preferably of fabric rubber; the provision of a harness of the class described which is water-proof, rust-proof, requiring 10 no oiling and which is of great tensile strength throughout; the provision of a harness of the class described which may have component parts made of indefinite length in one homogeneous piece, particularly such 15 parts as the traces and reins and blinders; the provision of a device of the class described which will admit of vulcanizing certain portions so that ripping of stitches and the like is eliminated and the provision of a 20 device of this class of harness which is adapted to be manufactured more economically with a consequent saving to the purchaser. Other objects will be in part obvious and in 25 part pointed out hereinafter.

25 The invention accordingly comprises the elements and combinations of elements, features of construction, and arrangements of parts which will be exemplified in the structure hereinafter described, and the scope of 30 the application of which will be indicated in the following claims.

In the accompanying drawings, in which is illustrated one of various possible embodiments of the invention,

35 Fig. 1 is a perspective view showing the harness applied to a horse;

Fig. 2 is a cross section taken on line 2—2 of Fig. 1, illustrating a part of the construction; and,

40 Fig. 3 is a section taken on line 3—3 of Fig. 1 illustrating another part of the construction.

45 Referring now more particularly to Fig. 1, there is illustrated at numeral 1, an animal such as a horse, to which the present invention applies. The present harness comprises the head harness 3, the breast harness 5 and the body harness 7, only a portion of which latter harness is shown.

50 The head harness 3 includes the reins 9,

crown piece 11, front pieces 13, the blinders 15, cheek piece 33 and the throat latch 17, said parts being flexible.

The breast harness 5 includes the ordinary collar with traces or tugs 19, the latter being 55 flexible.

The body harness 7 includes parts such as the saddle piece 21, breeching and hip strap 23, and the other flexible parts.

One of the primary features of this invention is that the parts above-named and other parts cooperating therewith excluding the collar, are substantially made of rubber, preferably fabric rubber, as distinguished from leather or the cord type of rubber. I obtain 60 the rubber in sheet form in the desired color and manufacture the harness therefrom, and if desirable, the color may be such as to resemble leather in appearance. I sew the parts where it is profitable and safe to do so. Certain seams which tend to rip and tear in service are sewn and/or vulcanized preferably 65 the latter. In Fig. 2, which shows a cross section of a blinder, for instance, I bend a sheet of rubber over upon itself and vulcanize 70 it at the surface 25. In leather blinders a thin piece of iron is used between the two pieces of leather, which are stitched around the edges to hold said iron piece in place. There is a tendency for this stitching to rip, thus 75 exposing the iron piece and causing an ugly appearance as well as unsatisfactory blinders. By the present invention, the iron piece, stitching and any ripping tendency is eliminated.

80 The front pieces 13 are attached to the blinders 15 by inserting said pieces into a recess 27 left between the sheets forming the blinder and subsequently stitching for a short distance as shown at numeral 29 in Fig. 1, 85 in order to fasten the front pieces in place. The blinders 15 are similarly stitched to the cheek pieces 33, as illustrated at numeral 33. Stitching is used in these instances in preference to vulcanizing, inasmuch as there is 90 no tendency for this joining to rip open in service operation.

95 It will be understood that the rubber fabric is folded in places, in order to permit the application of buckles and similar fastening de- 100

vices illustrated in the drawings. These buckles, however, are only such as are used for looping the reins, traces and the like upon themselves so as to vary their length to suit different harnessings, or for making ordinary fastenings.

In Fig. 3 is shown the homogeneous construction of the piece forming the reins 9. In this connection it should be noted that 10 reins such as 9 and traces or tugs 19 must sometimes be formed in rather long lengths where a plurality of horses are being driven in tandem teams and the like. When leather was used for the harness, it was necessary to fasten several lengths together in order 15 to form a proper length for the reins 9 or the traces 19. This was because the skin from an animal provides only a predetermined length of leather. With the present 20 rubber construction, a single homogeneous length of fabric rubber may be used without including any breaks or fastenings such as gluing joints, stitching or the like.

Other advantages are that this harness may 25 be manufactured at a fraction of the cost of a leather harness. Furthermore, no oiling of the harness is required as is the case with a leather harness. Leather harnesses crack unless oiled from time to time, but the rubber 30 will not be so affected. The rubber is also waterproof and proof against attack by rust from the metal parts associated therewith.

Another feature to be noted is that the rubber fabric has a greater tensile strength than 35 leather; further, the strength of the rubber fabric is uniform throughout its length, while the strength of the leather varies from place to place.

It will be readily understood that the 40 elements comprising the tugs or traces 19 are preferably made of heavier fabric than the other elements. In order that this may be done, these parts are manufactured from a single piece, strength being obtained by vulcanizing without stitching. It will be readily 45 appreciated that the vulcanized rubber fabric is a homogeneous material which is not as apt to come apart or break under tension as is leather.

50 In the present invention no laps will come unsewed and catch in other parts of the harness. There is no chance of ripping, because stitching is replaced by vulcanizing where rips tend to occur.

55 I have found that the present invention is particularly adaptable to work harness. In such case when a leather harness is used, it is often necessary to use heel chains in order to attain the desired trace strength. With 60 the present invention these harmful heel chains may be abolished and the full length trace substituted with no chain at all yet at the same time the full trace strength is attained.

65 In view of the above, it will be seen that

the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

70 I claim:

75 1. A rein comprising a strip of fabric, said fabric being completely enclosed in an envelope of vulcanized rubber, said rubber being vulcanized into said fabric whereby a 80 homogeneous material is obtained.

85 2. A harness rein comprising a fabric base in strip form, said fabric base being entirely covered with a layer of vulcanized rubber.

90 In testimony whereof, I have signed my 85 name to this specification this 30th day of July, 1929.

95 ALBERT W. GODFREY.
